CLAIM

I claim the ornamental design for a nestable bin cup, as shown and described.

DESCRIPTION

FIG. 1 is a top right perspective view of a nestable bin cup.

FIG. 2 is a bottom left perspective view thereof.

FIG. 3 is a top plan view thereof.

FIG. 4 is a bottom plan view thereof.

FIG. 5 is a front plan view thereof.

FIG. 6 is a rear plan view thereof.

FIG. 7 is a side plan view thereof.

FIG. 8 is a top left perspective view thereof showing a second cup stacked above; and,

FIG. 9 is a top left perspective view thereof showing a second cup stacked above.

The broken lines are for the purpose of illustrating the environment of the article only and form no part of the claimed design.
